UNITED STATES PATENT OFFICE.

PERRY SIMONS, OF ROSE, KANSAS.

DISH-WASHER.

1,199,211.

Specification of Letters Patent. Patented Sept. 26, 1916.

Application filed May 19, 1916. Serial No. 98,638.

To all whom it may concern:

Be it known that I, PERRY SIMONS, a citizen of the United States, residing at Rose, in the county of Woodson, State of Kansas, have invented certain new and useful Improvements in Dish-Washers; and I do hereby declare the following to be a full, clear, and exact description of the invention, such as will enable others skilled in the art to 10 which it appertains to make and use the same.

This invention relates to dish washing machines, and has for its primary object to provide a simple and improved mechanism 15 whereby a quantity of dishes and other table articles may be quickly and easily cleansed and rinsed with but little trouble on the part of the operator.

A further object of the invention is to 20 provide a device of this character which is equipped with improved trays or racks for holding the dishes in such manner as to prevent breakage of the dishes during the washing operation.

25 A still further object of the invention is to provide a machine of this type which is so arranged as to prevent the seepage or splashing of water from the machine when the latter is in operation. The arrangement 30 is furthermore such a one that the dishes are rotated around a horizontal axis, this construction creating a greater agitation of the water, and causing the dishes to be lifted from the water and plunged therein in rapid 35 succession, so that an increased cleansing action is secured.

A still further object of the invention is 40 to provide a device of this character which is capable of readily accommodating dishes of various shapes and constructions without danger of breakage of the same during the operation, and which is further equipped with improved means for readily removing the dishes from the trays or racks and the 45 machine after the cleansing operation has been performed.

A still further object of the invention is to provide a device of this character which is of extremely simple construction, which is

of inexpensive construction, which is composed of but few readily assembled parts all so arranged as to prevent breakage or derangement of the same, which is easy of operation, and which will prove thoroughly efficient in the attainment of the ends for 55 which it is designed.

With these objects in view, together with others which will appear as the description proceeds, the invention resides in the novel combination and arrangement of parts, all 60 as will be described more fully hereinafter, illustrated in the drawings and particularly pointed out in the claims.

The invention will be best understood by reference to the accompanying drawings, 65 wherein:

Figure 1, is a side elevation of a dish washing machine embodying my invention, Fig. 2, is an end view of the device, Fig. 3, is a longitudinal vertical sectional view 70 taken on line 3—3 of Fig. 2, Fig. 4, is a vertical transverse sectional view taken on line 4—4 of Fig. 1, Fig. 5, is a detail view of the rotary dish containing frame, and Fig. 6, is a similar view of one of the dish containing 75 racks or trays, Fig. 7 is an end view of the drum and Fig. 8 is an end view opposite to that of Fig. 7.

Referring now more particularly to the drawings, 7 indicates generally the casing 80 of the washing machine, the said casing comprising upper and lower shell members 8 and 9 respectively, which members are semi-cylindrical in shape and cooperate when properly assembled in forming the casing or 85 drum 7. The lower shell is formed preferably of thin metal, having heads 10 at its ends, legs 11 being secured to the said heads to support the lower casing portion above the floor. The inner faces of the heads 10 90 are cut away to provide laterally disposed shoulders 12 upon which the lower portions of the upper shell are adapted to rest. The exterior longitudinal edges of the lower shell member are provided with brace members 13, the said members connecting the heads 10, and the extremities of the metal forming the lower shell pass behind the said 95

brace members and are curved outwardly as at 14 to overlie the members 13. Extending longitudinally of the said lower shell upon opposite sides thereof and spaced 5 slightly below the upper edges of the shell member are retaining strips 15. A band 16 extends circumferentially of the lower shell intermediate the ends of the latter and is secured at its ends to the brace members 13 10 and supports the intermediate portion of the shell member. At the lowermost portion of the shell member and communicating with the interior thereof is a drain cock 17 whereby the water within the receptacle may 15 be readily drained therefrom.

Secured upon the exterior of the heads 10 and disposed vertically thereon are plate members 18, the latter being disposed between the ends of the supporting legs 11. 20 The uppermost portion of these plate members and the adjacent upper edge of each of the heads is cut away to provide a bearing, the bearing upon each edge being aligned longitudinally of the casing and disposed 25 centrally thereof. Drip pans 19 are secured to the outer faces of the plate members 18, the said drip pans being formed around the bearing on the said plates, and having their outer edges turned upwardly or flanged as 30 at 20, the lowermost portion of each drip pan being restricted and bent upon itself to form a tube 21 which directs the water which may be collected upon the drip pans to a suitable catch basin placed beneath the 35 casing.

The upper shell 8 is of substantially the same shape as the above described lower casing. This shell is formed of sheet metal curved into semi-cylindrical shape, heads 22 40 being arranged at the ends of the shell to close the latter, and flanges 23 depend from the lower transverse edges of the heads 22 to rest upon the shoulders 12 on the heads 10 of the lower section of the casing. The heads 22 also provide outwardly projecting shoulders 24 which are adapted to seat upon the upper edges of the heads 10 of the lower casing member. The flanges 23 are notched as shown to align with the bearing portions 50 formed in the heads 10 of the lowermost casing member. The longitudinal ends of the shell of the upper member project slightly beyond the lowermost extremity of the heads 22, the said projecting portion being 55 adapted to fit between the sheet metal forming the body portion of the lower casing and the retaining strips 15 within the latter. By flaring the ends 14 of the lowermost casing it is apparent that the top member may be 60 readily inserted within the lower member, and by interlocking the protruding longitudinal ends of the upper shell between the lower shell and retaining strips 15 it is seen that water within the casing will be pre-

vented from splashing therefrom at the 65 juncture of the upper with the lower shell. By interlocking the head members of the upper and lower shells as above described, the connection between the said members is made water-tight. A funnel 25 is arranged 70 in the uppermost portion of the upper shell intermediate the ends of the latter, the said funnel communicating with the interior of the casing to permit of water or cleansing fluid to be readily introduced therein. The 75 heads 22 may be equipped with handles 26 to be grasped in adjusting the upper shell to the lower casing member or in removing the same therefrom.

Arranged within the above described casing or drum is a frame 27. This frame is formed of foraminous material such as heavy wire netting and is in cylindrical form, heads 28 closing the ends of the cylindrical frame as shown. A shaft 29 extends 85 centrally and longitudinally of the frame 27, and rests at its ends in the bearing portion formed in the heads 10 of the lower shell member. This shaft is fixed to the frame so that rotary movement of the said shaft will 90 revolve the frame 27 within the washer casing. One end of the shaft may be equipped with a crank 30 whereby the shaft may be manually rotated. The opposite end of the shaft is provided with a belt pulley 31 to 95 enable the shaft to be operatively connected with an engine or motor. In the present embodiment of the invention the shaft is squared inwardly from the journaled portions, the said squared portions extending 100 through similarly formed apertures in the frame heads. If desired, the shaft need not extend throughout the length of the frame 27, but may terminate at its heads. The frame 27 is divided centrally and longitudinally by a sheet of foraminous material or fabric 32, brace rods 33 connecting the heads 28 upon each side of the dividing fabric to support the latter. The cylindrical frame is thus divided into upper and lower compartments, and the heads are correspondingly sectioned to permit the sections to be hinged to open the compartments. In the form shown, the sections are hinged at 34 to enable the said upper and lower sections to 115 be opened and closed but the sections might obviously be otherwise hinged. Hooks 35 are carried by the free ends of the hinged portions to engage with eyes 36 carried by the fixed portions of the head to enable the 120 hinged sections to be securely held in closed position. It is thus seen that access may be readily had to the oppositely disposed compartments in the cylindrical frame.

Dish trays or racks 37 are adapted for insertion within the cylindrical frame above described, and to support therein the dishes or other articles to be cleansed. These racks

are formed of a plurality of substantially circular foraminous or wire sheets, folded diametrically to provide spaced upwardly projecting leaves 38. The leaves thus formed are arranged in gangs, connecting members 39 being arranged between the various tray members to secure the same together. Trays thus formed used in connection with a rotary frame having the centrally disposed shaft 29 may be cut away at their lower portions to form a channel for the accommodation of the axle or shaft. These trays are of a width to permit of a number of gangs of the same being inserted side by side in each of the compartments of the rotary frame and of such diameter as to be held against undue radial movement by the covers of the rotary frame. A sufficient space is left between the said tray gangs to permit of the insertion of large platters, vegetable dishes, or other utensils varying in depth, thickness or shape. Cups and knives and forks may also be inserted in this space, while plates, saucers and other dishes of relatively thin construction are adapted to be inserted between the leaves of the various dish racks, to be held therein by frictional engagement between the leaves and the dishes. The gang members 39 limit the downward movement of the plates between the leaves so that the uppermost edges of the said plates protrude beyond the edges of the leaves to enable the same to be readily grasped when desired to remove the same from the device.

In operation, the rotary frame is placed within the lower casing member with the journaled portions of its axle or shaft resting in the bearing portions in the heads thereof. One side of the frame is then opened, and the trays or racks inserted therein. Dishes may then be placed within the said upper compartment between the gangs of trays, and between the leaves of the racks. When this compartment is filled the cover therefor is swung to closed position and the hooks 35 engaged within the eyes 36 on the frame head to hold the cover securely in closed position. The shaft may then be rotated sufficiently to expose the other side of the rotary frame, whereupon its compartment may in a like manner be filled with trays and dishes. When both closures for the frame are tightly closed, the upper shell member 8 may be placed upon the base shell and hot water introduced to the casing through the funnel 25. This water may be supplied with washing powder, soap or other cleansing material, and the shaft 29 is then rotated to thoroughly dash the dishes through the water. After the dishes have been relieved of food particles clinging thereto, the water may be drained from the casing through the drain cock 17. The cock

may then be closed and clean rinsing water introduced through the funnel 25. Further rotation of the shaft 29 will then thoroughly rinse the dishes, whereupon the upper shell 8 may be removed, and the dishes removed from the frame and dried. By the interlocking feature of the longitudinal edges of the upper shell with the lower shell it is apparent that splashing of water from the casing will be prevented. The drip pans 19 at the ends of the lower casing will catch and carry off any water that might seep through the bearing portions of the lower casing.

While I have herein shown and described a particular or preferred embodiment of the invention, I wish it to be understood that I need not confine myself to all the precise details of construction herein set forth by way of illustration as modification and variation may be made without departing from the spirit of the invention or exceeding the scope of the claims.

What is claimed is:

1. In a dish washing machine, the combination with a casing, a drum rotatable in said casing, said drum having a perforate periphery and consisting of an intermediate section and outer sections hinged to said intermediate section upon its opposite sides, a transverse foraminous partition longitudinally subdividing said intermediate section through the axis of the drum and dish racks mounted upon opposite sides of said partition.

2. In a dish washing machine, the combination with a casing, a shaft extending through said casing, a drum mounted upon said shaft and rotatable therewith, said drum having a perforate periphery, and consisting of an intermediate substantially rectangular section and outer segments hinged upon opposite sides of the intermediate section, a partition extending through said intermediate section and through the axis of the drum and longitudinally subdividing the latter into semi-cylindrical compartments and dish racks supported upon opposite sides of said partition, consisting of semi-circular spaced U-shaped troughs, and longitudinal rods connecting said troughs in gangs.

3. In a dish washing machine, the combination with a casing, a shaft rotatable in said casing, and a dish containing drum having a foraminous periphery, and consisting of an intermediate section which is carried by the shaft and outer sections hinged to said intermediate section, a partition subdividing the intermediate section through the axis of the drum into a pair of compartments, each of which has one of said hinged sections as a closure member.

4. In a dish washing machine, a dish rack

consisting of substantially circular sheets of foraminous material bent into U-shaped troughs and means for securing a plurality of said troughs side by side into a gang.

- 5 5. In a dish washing machine, a dish rack comprising a plurality of substantially circular sheets of material bent into U-shaped troughs and rods passed through the walls

of said troughs to connect them into unitary gangs.

In testimony whereof, I affix my signature, in the presence of two witnesses.
